CLAIM

The ornamental design for a fluid dispenser, as shown and described.

DESCRIPTION

FIG. 1 is a front view of the fluid dispenser.

FIG. 2 is a left side view of the fluid dispenser of FIG. 1.

FIG. 3 is a top view of the fluid dispenser of FIG. 1.

FIG. 4 is a bottom view of the fluid dispenser of FIG. 1.

FIG. 5 is a right side view of the fluid dispenser of FIG. 1.

FIG. 6 is a back view of the fluid dispenser of FIG. 1.

FIG. 7 is a three-dimensional view of the fluid dispenser of FIG. 1; and,

FIG. 8 is a three-dimensional view of the fluid dispenser of FIG. 1 from a different angle.

The broken lines depict portions of the fluid dispenser that form no part of the claimed design.
